CLAIM

The ornamental design for a in-vivo radiation counter or similar article, substantially as shown.

DESCRIPTION

FIG. 1 is a perspective view of an in-vivo radiation counter or similar device showing my new design;

FIG. 2 is a top plan view thereof;

FIG. 3 is a left side elevational view thereof;

FIG. 4 is a rear elevational view thereof;

FIG. 5 is a right side elevational view thereof; and

FIG. 6 is a bottom plan view thereof.

FIG-1

FIG-6

FIG. 2

FIG. 3

FIG. 5

FIG. 4
